UNITED STATES PATENT OFFICE.

WILLIAM E. LEMP AND EDWARD KEYLAND MCQUILLEN, OF MOBILE, ALABAMA.

VEHICLE DIRECTION-INDICATOR.

1,207,944.

Specification of Letters Patent. Patented Dec. 12, 1916.

Application filed February 28, 1916. Serial No. 80,882.

To all whom it may concern:

Be it known that we, WILLIAM E. LEMP and EDWARD KEYLAND MCQUILLEN, citizens of the United States of America, and residents of Mobile, county of Mobile, State of Alabama, have invented certain new and useful Improvements in Vehicle Direction-Indicators, of which the following is a full and clear specification.

10 The object of this invention is to provide a simple device of the headlight type which will not only serve as a headlight, but which may be operated to indicate to traffic officers and others the direction in which the vehicle intends or desires to go, as more fully hereinafter set forth.

20 In the drawings Figure 1 is a front elevation, partly broken away, of a device embodying our invention; Fig. 2 is a vertical sectional view thereof; Fig. 3 is a front elevation of a modified embodiment of the device; and Fig. 4 is a vertical sectional view of the device shown in Fig. 3.

25 In the drawing, *a* designates a casing enclosing a suitable illuminating device *b*, this device being preferably one or more electric lamps. The rear wall of this casing is concaved interiorly and is suitably brightened to thus convert it into a reflecting surface. 30 The front wall of the casing is preferably in the form of a door hinged at *c* to one of the vertical walls of the casing. The lower part *d* of this door is opaque and the upper part *e* is transparent and the illuminating device is desirably arranged immediately 35 back of the transparent panel *e*. Resting gravitationally in the chamber formed behind the opaque wall is a pair of sign panels *f* which, when in their lowered position, 40 are hidden behind the opaque panel *d*. Each of these sign panels is provided with transparent lettering indicating "right" or "left," the lettering on one being preferably red in color and the other being preferably 45 green, so that when one or the other panel is raised to a point opposite the transparent panel *e* the direction in which the vehicle intends going will be indicated to a person in front of the vehicle. When neither panel 50 *f* is raised, it will be understood that the vehicle is going straight ahead.

To raise the panels *f* and hold them temporarily in position behind the transparent panel *e*, we employ a pair of solenoids *g*, 55 one being fixed to the top of the headlight casing and the other one depending from

the bottom thereof. The core rod *h* of each of these solenoids is connected to one of the sign panels *f* midway between the ends of the panel, so that when either solenoid is energized its core will be drawn into the solenoid and thus raise the sign panel into operative position and hold it there so long as the solenoid remains energized. When the solenoids are deenergized, the panels *f* return by gravity to their inoperative position behind the opaque wall *d*. The core attached to each plate co-operates with its associated solenoid to maintain the plate in a vertical position at all times and it will be observed that by the employment of a single core connected to each plate midway between the ends of the plate and mounting the corresponding solenoid outside the casing, I produce an inexpensive and ornamental headlight, having a casing of minimum size, and in which the lifting, guiding and supporting devices for the plates are reduced to a minimum number of parts and do not materially interfere with the projection of the light rays. Any suitable circuit arrangement may be employed for energizing the solenoids, but in all cases it will be understood that the circuits will be so arranged that the solenoids may be operated 75 separately and not together. We prefer to arrange the circuits so that they may be closed by two push buttons arranged in such position on the vehicle that the chauffeur may conveniently operate either push button 80 with his foot and thus avoid removing his hands from the steering wheel. Current for energizing the solenoids may be taken from the battery carried on the motor vehicle.

85 A feature of importance in our device lies 90 in the fact that the sign panels are held in operation only so long as the current is on, the breaking of the circuit alone being sufficient to cause the sign panel to return to inoperative position. We have not illustrated any wiring arrangement, as it will be obvious that this forms no part of our invention, since the electric conductors may be arranged in a great variety of ways without departing from our invention.

100 It will be observed that another important feature lies in the fact that, when the panels are in their normally inoperative position, the cores are almost entirely outside of the coils, the lower core depending 105 below the lower coil, so that, when they are brought into operative position, the cores

will extend their full length within the coils and will therefore be sustained by the full electro-magnetic force of the coils. This arrangement permits us to operate the panels 5 by a single solenoid for each panel, and also to arrange the solenoids outside of the casing, so that the casing may be made sufficiently small in dimensions to be used as a headlight in addition to an illuminated 10 vice for the direction-panels. This arrangement also provides for utilizing the entire upper part of the casing for exhibiting the panels, the panels when in operative position covering the entire light-emitting opening 15 in the face of the casing. The only objection to this construction is that, when the upper solenoid is inoperative and its panel is down, its core *h* will extend vertically across the light-emitting part of the chamber; but this will not interfere with the 20 operation of the headlight, especially if two lamps are employed, one at either side of the core, as shown in dotted lines in Fig. 1.

In Figs. 3 and 4 we illustrate a type of 25 device in which but a single sign panel is embodied. With this single form of device, it will be necessary to employ two of the headlights, one at either side of the vehicle, one being provided with a "left" sign and 30 the other being provided with a "right" sign. This single type of device will be especially desirable where our indicating headlights are to be built into the vehicle at the factory. They are also especially desirable 35 where it is not desired to disturb the usual central headlight on the vehicle, this central headlight being in use at present on certain public vehicles. When a single type of device is used, we prefer providing means 40 for vertically guiding the panel in the headlight chamber; one form of such means consists of a pair of vertical wires *i* which are engaged by eyes *j* on the upper corners of the sign panel.

45 Having thus described our invention, what we claim is:

1. A signaling headlight, comprising a casing the front wall of which has an opaque lower panel and a transparent upper panel, 50 a light source and a light projecting reflector in the casing directly behind the transparent panel, a pair of signal plates normally gravitationally supported in said

casing behind said opaque panel, and means for raising said plates between the transparent panel and the light source embodying a solenoid mounted on top of the casing and a solenoid depending from the bottom of the casing, and a core connected to each plate intermediate its ends and coöperating with one 60 of the solenoids to raise the plate and to maintain it in a vertical position at all times, the lower core normally depending below the solenoid and the upper core normally depending across the transparent upper 65 panel.

2. A signaling headlight, comprising a casing the front wall of which has an opaque lower panel and a transparent upper panel, a light source and a light projecting reflector in said casing, a signal plate normally gravitationally held behind the opaque panel, a solenoid depending from the center of the bottom of the casing, and a core coöperating with the solenoid and connected 70 with the signal plate intermediate the ends thereof for raising the plate between the transparent panel and the light source and maintaining the plate in a vertical position at all times, said core normally depending 75 below the solenoid so that when the signal plate is raised the core will lie its full length within the solenoid.

3. A signaling headlight, comprising a casing having a front wall having a transparent upper panel and an opaque lower panel, a light source and a light projecting reflector in said casing directly behind the transparent panel, a signal plate normally held behind said opaque panel, a solenoid 85 mounted on top of the casing centrally thereof, and a core connected at its lower end to the plate intermediate the ends thereof and coöperating with the solenoid to temporarily raise the plate between the transparent panel and the light source and to maintain the plate in a vertical position at 90 all times.

In testimony whereof we hereunto affix our signatures this 25th day of February, 100 1916.

WILLIAM E. LEMP.

EDWARD KEYLAND MCQUILLEN.
